No. 806,063.

PATENTED NOV. 28, 1905.

F. CAMPBELL.
TOY PISTOL.
APPLICATION FILED OCT. 15, 1904.

UNITED STATES PATENT OFFICE.

FRANK CAMPBELL, OF CARLOOVER, VIRGINIA.

TOY PISTOL.

No. 806,063.

Specification of Letters Patent.

Patented Nov. 28, 1905.

Application filed October 15, 1904. Serial No. 228,581.

To all whom it may concern:

Be it known that I, FRANK CAMPBELL, a citizen of the United States, residing at Carloover, in the county of Bath and State of Virginia, 5 have invented new and useful Improvements in Toy Pistols, of which the following is a specification.

This invention relates to a toy pistol or gun; and its object is to provide a toy device of this 10 character which is simple in construction and composed of parts which may be readily assembled for production of the device and disassembled for repairs and which will simultaneously 15 expel a projectile and discharge a cap to simulate the action of an ordinary gun employing powder as the explosive charge.

With this and other objects in view, the invention consists of the features of construction, combination, and arrangement of parts 20 hereinafter fully described and claimed, reference being had to the accompanying drawings, in which—

Figure 1 is a view in side elevation of a pistol or gun constructed in accordance with my 25 invention. Fig. 2 is a top plan view of the same. Fig. 3 is a central vertical longitudinal section, such view showing one of the members of the body removed and the interconnecting parts in section. Fig. 4 is a de- 30 tail view of the plunger-locking plate or detent. Figs. 5, 6, and 7 are similar views of the clips or coupling devices employed for connecting the members of the body of the pistol. Fig. 8 is a detail view of the spring- 35 detent controlling the feed of the projectiles from the magazine to the discharge-bore of the barrel; and Fig. 9 is a section on line 9 9, Fig. 3.

The body of the gun or pistol is longitudinally divided and composed of two corresponding sections 1 and 2 of proper configuration to form the stock 3, grip 4, and barrel 5 of the arm. The meeting faces of the sections or members 1 and 2 of the arm are provided with mating grooves 6 and 7, which extend longitudinally from a point near the inner end of the stock to and through the outer end of the barrel and provide a magazine adapted to hold a series of projectiles 8, which 45 may be ordinary shot or other bodies of a form and character suitable for the purpose. Below the magazine 6 the barrel-sections of the members 1 and 2 are formed with corresponding mating grooves 9 and 10, which are dis- 50 posed in parallel relation to the forward half of the magazine and provide a discharge-bore

which receives the projectiles from the magazine and forms the chamber through which they are expelled from the arm. In the wall separating each groove or half of the magazine from the discharge-bore coincident notches are formed which provide a feed-passage 11, through which the shot contained in the magazine feed one by one to the discharge-bore. The stock and the grip portions of the 60 arm are hollowed or chambered to receive the inner portion of the trigger, the plunger-locking plate or detent and the connections which unite and hold in assembled relation the forward and rear portions of the members 1 and 2 of the arm, as will be hereinafter described.

In the bore formed by the grooves 9 and 10 reciprocates a plunger 12, which expels the shot therefrom, and from the rear portion of this plunger projects a shank 13, which is exposed on opposite sides through slots 14, formed in the barrel and stock portions of the members 1 and 2. The plunger 12 is preferably circular in cross-section to conform to the form of the discharge-bore, while the shank 13 is rectangular in cross-section and slides at its rear end in a guide-plate 15, extending transversely through the rear portion of the slots 14 and formed with a slot or opening 16 80 for the passage of said shank. The ends of the said plate 15 are bent at right angles to form clips 17, which embrace the outer opposite sides of the members 1 and 2 and serve to hold the upper rear portions of the same as- 85 sembed. The rear portions of the members 1 and 2 are provided with recesses forming a guide-slot 18, opening through the upper rear portions thereof and communicating with the rear portions of the slots 14, and said recesses 90 form a guide-opening for the passage of the rear portion of the shank 13. The shank 13 is provided at its forward end with lateral shoulders or projections 19, which limit its forward movement and serve as finger-pieces to 95 permit it to be slid rearwardly against the resistance of an impelling-spring 20, said spring surrounding said shank between the shoulders or projections 19 and the guide-plate 15. The trigger 21 is movable in slots 22 in the mem- 100 bers 1 and 2 and pivotally mounted upon a suitable stud 23. This trigger co-operates with a locking plate or detent 24, consisting of a substantially rectangular plate, as shown in Fig. 4, provided with an elongated rectangular slot 25. The edges of the plate 24 fit and slide in inclined guide-grooves 26, formed in the 105 110

members 1 and 2 and so disposed as to cause the plate 24 to extend at an angle to the shank 13 and to be engaged at its lower end by a portion of the trigger 21. The slot 25 is of such length as to permit the shank 13 to slide freely through the plate 24 and to permit said plate to have free movement to interlock with and release the shank 13. As shown, the forward portion of the shank 13 is provided with 10 a notch or recess 27, which is adapted to be engaged by the upper wall of the slot 25 of the plate 24 when the shank is drawn backwardly to compress the spring 20, so that the plate 24 will lock the shank against movement and retain the outer end of the plunger at a point just 15 in rear of the feed-slot 11, thus allowing one of the projectiles 8 in the magazine 6 to feed to the bore 9. The plate 24 normally rests upon the shank 13 and drops by gravity into the 20 notch 27 and may be lifted by operating the trigger 21 to disengage it from said notch, and thus permit the spring 20 to force the shank and plunger forwardly to expel the projectile from the magazine 6. The feed of the projectiles 25 from the magazine 6 is governed by a detent-spring 28, having an angularly-bent end 29 fitting in recesses in the mating members 1 and 2 below the feed-passage 11. Normally the free end of the spring 28 is forced down 30 by the plunger 12 to a point below the bore 9; but when the outer end of the plunger passes the detent upon the rearward movement of the shank 13 to set the device for action the spring 28 is released and moves up to the dotted-line position shown in Fig. 5, thus permitting but one of the projectiles 8 to feed down to the opening 11 and retaining the same in position for discharge under the action of the impelling-spring when the plate 24 is released by the trigger 21.

The rear portion of the shank 13 has an extension 30, projecting rearwardly from its lower edge and having an upwardly-bent end 31, corresponding in height or depth to the 45 shank and carrying a keeper pin or stud 32, the end of the shank being provided with a similar keeper pin or stud 33, disposed in alignment therewith. These pins or studs are adapted to engage openings in the ends of a 50 hammer 34, the said hammer consisting of a strip of metal bent to form a striking portion 35 and attaching ends or arms formed with openings by which it may be fitted upon the said pins 32 and 33. The striking portion 35 is of such form and size as to be received within a chamber 36, formed in the upper rear portion of the stock 3 above the grip 4, so that when a cap or other like explosive is placed within said chamber the striking portion 35 60 will come into contact with and fire the same, when the plunger is moved forward under the action of the impelling-spring and discharges the projectile previously fed into the bore 9. The ends or arms of the hammer spread apart 65 by the spring action of the strip of which the

hammer is made and engage the pins 32 and 33 and may be released from engagement with the pins by compressing them to permit the hammer to be detached, as will be readily understood.

In the operation of using the arm the magazine 6 is first filled with projectiles and the plunger drawn rearwardly through the medium of the finger-pieces 19 until the notch 27 comes into coincidence with the plate 24, whereupon said plate will drop down into engagement with the notch and lock the shank and plunger against forward movement under the action of the spring 20, which has been compressed by the rearward movement. 70 A cap or other explosive is then placed in the chamber 36, and then upon operating the trigger 21 the plate 24 will be forced upward in its guide-grooves and out of engagement with the notch 27, thus releasing the shank and permitting it to be forced forward by the spring 20, whereby the plunger expels the shot or projectile in the bore 9. Simultaneously with this action of the plunger in ejecting the projectile the striking portion 35 of the hammer comes 75 into engagement with the cap in the chamber 36 and fires the same, thus simulating the action of an ordinary gun using powder as the explosive charge. The front portions of the barrel-sections of the members 1 and 2 are provided 80 with transverse recesses 37 to receive the body portion of a clip 38 and shoulders 39 to form abutments for the angular arms 40 of said clip, the arms 40 being provided at their free ends with inturned hooks 41 to engage 85 behind said shoulders, and thus hold the parts in assembled relation. The clip 38 is made of spring metal, so that the arms 40 may have free resilient movement to snap into engagement with the shoulders 39 and to be forced 90 outwardly and released therefrom. It will be observed that the clip 38 not only connects the forward portions of the members 1 and 2, but forms a closure for the magazine 6, thus 95 preventing the escape of the projectiles 8. In replenishing the magazine the said clip is detached, the projectiles fed into the magazine, and the clip then applied to close the magazine and hold the forward portions of the members 1 and 2 connected.

In addition to the guide-plate and clip 15 and the clip 38 a pair of couplings 42 are employed in connection with a suitable connection between them to hold the members of the arm assembled. Each of these couplings 42 comprises a body portion in the form of a shank having at one end a hook 43 and at the other end oppositely-arranged wings or flukes 44, which are bent or curved in a forward direction or toward the hook 43. These couplings are disposed, respectively, at the forward portion of the stock 3 and base of the grip 4, and their shanks or arms project inwardly through slots formed in the sections 1 and 2, while their wings or flukes 34 em- 100 105 110 115 120 125 130

brace the opposite sides of the members 1 and 2 and serve as clips to hold them in mating relation. The couplings are connected interiorly by a union or connection comprising wires or cords 45 46, attached to the hooked portions 43 thereof and extending through the cavities in the stock portions 3 and connected at their inner ends by a spring 46'. This spring 46' forms a flexible connection, which permits the couplings to be detached when it is desired to disassemble the arm and to be reinserted to hold the members of the arm assembled, the action of the spring when contracting maintaining the two couplings in engaging position.

From the foregoing description, taken in connection with the accompanying drawings, the construction and mode of operation of my improved pistol or gun will be readily understood, and it will be seen that the parts of the same may be readily assembled, thus allowing the device to be conveniently and cheaply manufactured, and may also be quickly and conveniently disassembled to enable the interior parts to be removed for repairs. Changes in the form, proportions, and minor details of construction may be made within the scope of the invention without departing from the spirit or sacrificing any of the advantages thereof.

Having thus described the invention, what is claimed as new is—

1. An arm of the character described composed of sections having grooves forming a discharge-bore and a magazine in communication with each other, the outer ends of the barrel portions of said sections being provided with transverse registering grooves across the inlet of the magazine and locking-shoulders in rear of said grooves, and a clip seated in said grooves and having rearwardly-extending arms provided with inwardly-projecting hooks engaging said shoulders, said clip thus serving to connect the forward ends of the sections and close the inlet to the magazine.

2. In an arm of the character described, the combination of a body having a discharge-bore, a plunger operating in said bore, a shank slidably mounted in the body and connected with said plunger, a detent-plate hav-

ing an opening for the passage of the shank and arranged to slide at an angle thereto, said plate being adapted to engage a portion of the shank to hold the same and the plunger retracted, a spring for projecting the plunger and the shank, and a trigger for sliding and retracting said detent-plate.

3. In an arm of the character described, the combination of a body having a discharge-bore and a receptacle for a detonator, a plunger operating in the discharge-bore, a shank mounted to slide within the body and connected with the plunger, said shank having a notch or shoulder and a hammer-supporting portion, a hammer mounted upon said supporting portion and adapted upon the outward movement of the plunger to enter said receptacle, a spring co-operating with the shank to project the same and plunger, a sliding detent-plate having an opening for the passage of the shank and adapted to engage the notch or shoulder therein to hold the shank therein, and a trigger for sliding and releasing said detent-plate.

4. In an arm of the character described, the combination of a projectile-expelling device, a shank connected thereto and provided with a notch or shoulder, a spring for projecting said shank and expelling device, a detent-plate having an opening for passage of the shank and arranged to slide at an angle thereto, said plate being adapted to engage said shoulder or opening to hold the shank and expelling device retracted, a trigger for sliding the plate out of engagement with said notch or shoulder.

5. An arm of the character described comprising members having recesses forming a discharge-bore and receptacles for its operating parts, clips engaging the base portions of said members, and a connection between said clips, said connection having a contractible and expansible portion, whereby the clips are held in engagement and may be drawn outward for removal, substantially as described.

In testimony whereof I affix my signature in presence of two witnesses.

FRANK CAMPBELL.
